LIGATOR

David J. Calicchio, Boston, Mass.

Application November 2, 1949, Serial No. 125,079

5 Claims. (Cl. 128—326)

1

The present invention relates to surgical instruments, and more particularly to ligators, especially ligators for tying deep ligatures.

Though there is no difficulty involved in tying ordinary knots under ordinary conditions, difficulties do arise when it becomes necessary to make a tie in some deep region of the body, as frequently occurs in surgery of the abdomen, tonsillectomies, and the like. In order that the surgeon may have a clear and free field in which to work, he must tie off all the blood vessels in that field, but it taxes the skill of the ablest surgeons to do this in cases where the anatomical parts are almost inaccessible and the fingers are obliged to work almost blindly.

It has accordingly been proposed to provide instruments to aid in this work. Unfortunately, however, these prior proposals have been so impracticable that, so far as known, they have never gone into use.

One such proposal, for example, has involved passing through an opening at the forward end of a base member a ligature one end of which is provided with a slip knot for encircling the severed blood vessel to be tied while held clamped by a hemostat, and tying the other end of the ligature to a member that is slidably mounted on the base member. The proposal was to tighten the knot by sliding the slideable member along the base member. The forward end of the proposed base member, however, was of so small dimensions as to involve danger of the surgeon, during the manipulation of the instrument, puncturing the body tissues. The proposed instrument was so short, moreover, that the knot could not be tightened merely by sliding the slideable member on the base member to the limit of its slideable movement. It became necessary, therefore, to discard the instrument at a time when the knot was still not yet tight, and to complete the work of tying the knot without its aid. The proposed instrument was of such nature, furthermore, that the free end of the slip knot would frequently get in the way of the field of view of the operation, and this would necessitate stopping the work in order to remove it out of the way. There were other disadvantages also.

An object of the present invention, therefore, is to provide a new and improved ligator that shall be entirely free of all these disadvantages.

Other and further objects will be explained hereinafter and will be particularly pointed out in the appended claims.

The invention will now be more fully explained

2

in connection with the accompanying drawings, in which:

Fig. 1 is a plan of a ligator embodying the present invention, with a ligature applied thereto, ready for tying a bleeding point; Fig. 2 is a side elevation of the same; Figs. 3 and 4 are sections taken upon the lines 3—3 and 4—4, respectively, of Fig. 2, looking in the direction of the arrows; Fig. 5 is a similar section taken upon the line 5—5 of Fig. 1, looking in the direction of the arrows; Fig. 6 is a perspective illustrating the operation of the ligator of the present invention; and Fig. 7 is a fragmentary perspective, upon a larger scale, of the lower portion of the ligator and adjacently disposed parts illustrated in Fig. 6.

The ligator of the present invention comprises a base member 1 upon which is slidably mounted a member 10.

20 The base member 1 is provided with a rearwardly disposed thumb rest 6, shown in the form of a ring, and a forwardly disposed portion 3 capped by a terminal portion 4 provided with a terminal collar 5. The portion 4 is fixed by means of a stem 19 in a recess 20 provided at the extreme end of the forwardly disposed portion 3. The terminal collar 5 is of substantial area, in order to provide a blunt portion which, because of the bluntness, may engage the tissues 25 of the patient without danger of perforating them. At diametrically opposite points, the collar 5 is provided with the two openings 21. Through one of the openings 21, which may be termed a first opening, may be threaded a ligature 22 the forward end of which is provided with a slip or other loose knot 23, beyond which extends loosely a ligature loop 24. The other opening 21, which may be termed a second opening, is adapted to receive the free end 22 of the slip 30 knot 23. The free end 22 of the slip knot 23 is thus forced away, so as not to obstruct the surgeon's view of the field of the operation, and so as not to interfere with the manipulation of the instrument.

45 The base member 1 is shown cylindrical, and mounted in a correspondingly cylindrical bore of the slideable member 10. In order that the ligature may become subjected to straight-line tension during the tightening of the slip knot 23, it is desirable that the slideable member 10 be non-rotatable during its slideable movement. In order to prevent such rotation of the slideable member 10 during its slideable movement upon the base member 1, the base member 1 is shown flattened 50 at 2, and the flat surface is engaged slideably

a correspondingly flattened surface of a filler member 32 that is held in place in the cylindrical bore of the slidable member 10 in any desired manner, as by means of a rivet 31.

The slidable member 10 is provided with a finger rest, shown constituted of two finger rings 9. In response to pressure exerted by the thumb on the thumb rest 6 and by any two fingers upon the finger rings 9, the member 10 will be caused to slide rearwardly along the base member 1 toward the thumb rest 6. Since the slidable member 10 cannot rotate during its slidable movement upon the base member 1, it is desirable, in order to provide for relative twisting movement of the thumb and the fingers, to render the thumb rest 6 freely rotatable. According to the illustrated embodiment of the invention, this result is attained by freely mounting the rear end of the base member 1 rotatably in a longitudinally disposed cylindrical socket of a forward extension 7 of the thumb rest 6. A rivet 8 projects through a side wall of the extension 7 into a peripherally disposed groove 30 provided at the rear end of the base member 1. The rivet 8, though preventing detachment of the parts, permits of the thumb rest 6 rotating freely about the axis of the cylinder of the base member 1.

The ligature loop 24 is originally made large enough to encircle a hemostat 35, shown clamped to a bleeding point 36. After the hemostat 35 has been carried entirely through the loop 24, the loop 24 is contracted until it engages the clamped blood vessel 38. This may be effected by slidably looping an intermediately disposed portion 25 of the ligature next adjacent to the slip knot 23 around a pulley-like-shaped portion 42 of a projection 11 of the slidable member 10, then carrying the ligature forward again, as shown at 27, and applying tension. The slidable member 10 is thus forced on the base member 1, into contact with a stop member 13, as illustrated in Figs. 1 and 2. The ligature 25 is then wound several times around a projecting post 16 disposed intermediately of the base member 1, as shown at 28, after which its free rear end 29 is fastened in place in an intermediately disposed slit 15 provided in a portion 14 of the projecting post 16.

The surgeon now introduces his thumb into the thumb ring 6 and two fingers into the finger rings 9 to exert pressure between his thumb and his fingers. This results in drawing the slidable member 10 rearward, out of contact with the stop member 13, from the position of Figs. 1 and 2 toward and beyond the position illustrated in Fig. 6. The consequent tension introduced in the ligature, as the collar 5 presses against the slip knot 23, tautens the ligature loop 24 to effect the tightening of the slip knot 23. The hemostat 35 and the ligature may now be removed, after which the ligature and its free end 22 may be severed.

The projection 11 is shown fixed to the slidable member 10 by providing it with a projecting tongue 33 that is secured in a correspondingly shaped recess 34 of the slidable member 10. The projection 16 is shown similarly secured in place by providing it with a post 17 and securing it in a correspondingly shaped recess 18 of the base member 1.

By reason of this construction, the length of the ligature that may be taken up during the above-described tightening of the loop 24 is double the distance of slidable travel of the slidable member 10. If the free end 29 of the

ligature were fastened to the projection 11, instead of to the post 16, this length, of course, would be the same as the distance of slidable travel of the member 10. Under such circumstances, the slidable member 10 might travel into contact with the extension 7 of the thumb rest 6 without sufficiently tightening the slip knot 23. The present invention overcomes this danger.

It is possible, of course, to provide for tripling, or even quadrupling, the length of the ligature taken up during the slidable movement of the slidable member 10 by looping the ligature, not only around the projection 11, but also around the post 16, as well. The free rear end 29 of the ligature would then be secured to the slidable member 10, instead of to the post 16 of the base member 1. It is found, in practice, however, that the doubled length of ligature obtained by the described construction is quite sufficient for ordinary purposes.

The ligature of the present invention is particularly adapted for tying bleeding points 36 in deep anatomical regions, as indicated by the cross sectional configuration 37, where it is difficult for the surgeon to introduce his fingers, and where it is difficult for him to work freely.

Modifications will occur to persons skilled in the art and all such are considered to fall within the spirit and scope of the invention as defined in the appended claims.

What is claimed is:

1. A ligator comprising a base provided with a rearwardly disposed thumb rest and a forwardly disposed single-ended terminal portion provided 35 with a terminal collar having a first opening through which may be loosely passed a ligature the forward end of which is provided with a slip knot and a second opening for receiving the free end of the slip knot, and a member provided with 40 a finger rest and means for fastening the rear end of the ligature, the member being rearwardly slidable upon the base in response to pressure exerted by the thumb on the thumb rest and by a finger upon the finger rest to draw the ligature through the first opening in order that the slip knot may engage the terminal portion to become tightened, and the terminal collar being of substantial area to render the ligator blunt at its 45 extreme forward end to minimize danger of the said extreme forward end perforating tissue that it may engage.

2. A ligator comprising a base provided with a rearwardly disposed thumb rest and a forwardly disposed single-ended terminal portion provided 55 with a terminal collar having a first opening through which may be loosely passed a ligature the forward end of which is provided with a slip knot and a second opening for receiving the free end of the slip knot, and a member provided with 60 a finger rest and means for slidably looping an intermediately disposed portion of the ligature as well as means for fastening the rear end of the ligature, the member being rearwardly slid- 65 able upon the base in response to pressure exerted by the thumb on the thumb rest and by a finger upon the finger rest to draw the ligature through the first opening in order that the slip knot may engage the terminal portion to become tightened, and the terminal collar being of substantial area 70 to render the ligator blunt at its extreme forward end to minimize danger of the said extreme forward end perforating tissue that it may engage.

3. A ligator comprising a base provided with a rearwardly disposed thumb rest, and a forwardly 75 disposed single-ended terminal portion having

a first opening through which may be loosely passed a ligature the forward end of which is provided with a slip knot and a second opening for receiving the free end of the slip knot, a member provided with a finger rest and means for slidably looping an intermediately disposed portion of the ligature as well as means for fastening the rear end of the ligature, the member being rearwardly slideable upon the base in response to pressure exerted by the thumb on the thumb rest and by a finger upon the finger rest to draw the ligature through the first opening in order that the slip knot may engage the terminal portion to become tightened, and the terminal portion being of substantial area to render it blunt at its extreme end to minimize danger of its perforating tissue that it may engage.

4. A ligator comprising a base provided with a rearwardly disposed thumb rest, intermediately disposed means for fastening the rear end of the ligature and a forwardly disposed single-ended terminal portion having a first opening through which may be loosely passed a ligature the forward end of which is provided with a slip knot and a second opening for receiving the free end of the slip knot, a member non-rotatably slideable with respect to the base provided with a finger rest and means for slidably looping an intermediately disposed portion of the ligature as well as means for fastening the rear end of the ligature, the member being rearwardly slideable upon the base in response to pressure exerted by the thumb on the thumb rest and by a finger upon the finger

rest to draw the ligature through the first opening in order that the slip knot may engage the terminal portion to become tightened, and the terminal portion being blunt to minimize danger of its perforating tissue that it may engage.

5. A ligator comprising a base provided with a rearwardly disposed portion and a forwardly disposed single-ended terminal portion provided with a terminal collar having a first opening through which may be loosely passed a ligature the forward end of which is provided with a slip knot and a second opening for receiving the free end of the slip knot, and a member provided with means for fastening the rear end of the ligature, the member being rearwardly slideable upon the base to draw the ligature through the first opening in order that the slip knot may engage the terminal portion to become tightened, the terminal collar being of substantial area to render the ligator blunt at its extreme forward end to minimize danger of the said extreme forward end perforating tissue that it may engage.
